(57) **CLAIM**

I claim the ornamental design for a telescoping task light, as shown and described.

DESCRIPTION

FIG. 1 is a perspective view of a telescoping task light, showing my new design, taken from above and to the right-front side;

FIG. 2 is another perspective view of the telescoping task light shown in FIG. 1, taken from below and to the right-front side;

FIG. 3 is another perspective view of the telescoping task light shown in FIG. 1, taken from above and to the left-rear side;

FIG. 4 is a front elevation view of the telescoping task light shown in FIG. 1;

FIG. 5 is a rear elevation view of the telescoping task light shown in FIG. 1;

FIG. 6 is a right side elevation view of the telescoping task light shown in FIG. 1, with a left side elevation view being a mirror image thereof;

FIG. 7 is a top plan view of the telescoping task light shown in FIG. 1;

FIG. 8 is a bottom plan view of the telescoping task light shown in FIG. 1; and,

FIG. 9 is a right side elevation view of the telescoping task light shown in FIG. 1, showing its telescoping arm assembly in an extended position.

The broken lines shown in the drawings are for illustrative purposes only and form no part of the claimed design.
